Primary Examiner — Catherine R Oliver-Garcia*(74) Attorney, Agent, or Firm* — Walter J. Tencza, Jr.(57) **CLAIM**

We claim the ornamental design for the release holster apparatus, as shown and described.

DESCRIPTION

FIG. 1 is a perspective view of the release holster apparatus shown in use, in a closed state;

FIG. 2 is a front, top and right perspective view, shown in an open state;

FIG. 3 is a front, top and right perspective view, shown in a second open state;

FIG. 4 is a right side elevation view, shown in the first open state of FIG. 2;

FIG. 5 is a left side elevation view thereof;

FIG. 6 is a top plan view thereof;

FIG. 7 is a bottom plan view thereof;

FIG. 8 is a front elevation view thereof; and,

FIG. 9 is a rear elevation view thereof.

The person's wrist, arm, and hand shown in FIG. 1 is shown in broken lines for illustrative purposes only and forms no part of the claimed design.
